UNITED STATES PATENT OFFICE.

JESSE W. JOHNSON, OF INDIANAPOLIS, INDIANA, ASSIGNOR TO W. H. JOHNSON & SON CO., OF INDIANAPOLIS, INDIANA.

DESIGN FOR A SIDE OR BRACKET FOR RADIATOR-SHIELDS.

41,608.

Specification for Design.

Patented July 25, 1911.

Application filed April 24, 1911. Serial No. 623,120. Term of patent 14 years.

To all whom it may concern:

Be it known that I, JESSE W. JOHNSON, a citizen of the United States, residing at Indianapolis, in the county of Marion and State of Indiana, have invented a new, original, and ornamental Design for a Side or Bracket for Radiator-Shields, of which the following is a specification, reference being had to the accompanying drawing, forming a part hereof.

The figure is a perspective view of a side or bracket for radiator shields, showing my design.

I claim:

The ornamental design for a side or bracket for radiator shields as shown.

JESSE W. JOHNSON.

Witnesses:

F. W. WOERNER,
Jos. A. MINTURN.
